UNITED STATES PATENT OFFICE.

WILLIAM JOSEPH STILL, OF EALING, ENGLAND.

APPARATUS FOR TRANSMITTING HEAT FROM ONE FLUID TO ANOTHER.

No. 880,417.

Specification of Letters Patent.

Patented Feb. 25, 1908.

Application filed March 9, 1905. Serial No. 249,827.

To all whom it may concern:

Be it known that I, WILLIAM JOSEPH STILL, a subject of the King of Great Britain and Ireland, residing at Ealing, in the county of Middlesex, England, have invented an Apparatus for Transmitting Heat from One Fluid to Another, of which the following is a specification.

My invention has for object, *inter alia*, to transmit heat from one fluid to another in such a way that the metal employed is used to its full advantage, a smaller space is occupied, and the cost is reduced. For this purpose, in apparatus according to this invention, which is made of the known type comprising a wall between the two fluids and heat conductors in heat-conducting connection with that wall and projecting therefrom into one and it may be both of the fluids, the heat-conductors are so constructed and arranged that they extend into one of the fluids at different parts thereof to different extents and more or less according as those parts differ respectively less or more in temperature from the portions of the conductors in contact therewith. The areas of the conductors are thus in accord with the rate of heat transference between the conductors and the fluid into which they project; as far as practicable the areas of the conductors in contact with the fluid are inversely proportional to the differences of temperature between the plates and the parts of the fluid into which they project; in the case of conductors projecting to different extents into the hotter of the two fluids, the conductors will project into different parts thereof more or less according as those parts are respectively lower or higher in temperature.

The accompanying drawings illustrate examples of apparatus in accordance with this invention.

Figure 1 is an elevation, partly sectional, of an example of heat transmitting section adapted for the generation of steam; Fig. 2 is a transverse section of the same; Fig. 3 is an end elevation of a tee-headed rod by means of which the apparatus shown in Figs. 1 and 2 can be cleaned; Fig. 4 is a side elevation of said rod; Fig. 5 represents in plan, a steam generating section that is constructed as shown in Figs. 1 and 2 but is provided with a dummy end to facilitate cleaning. Figs. 6 and 7 are cross sectional elevations taken on the lines A A and B B of Fig. 5; Figs. 8 to 13 are longitudinal central sections

through portions of apparatus such as shown in Figs. 1, 2, 5, 6 and 7 illustrating alternative constructions of the heat transmitting plate or plates and intervening rings; Fig. 14 is a transverse section of apparatus similar to that shown in Figs. 1 and 2, but comprising plates and rings of oval form. Fig. 15 is a transverse section of similar apparatus wherein the plates and rings are of rectangular form; Figs. 16 and 17 are respectively a transverse section and a plan of a modified construction of steam generating apparatus; Fig. 18 is a transverse section of a further modification thereof; Figs. 19 and 20 are respectively an end and a side elevation of a wire brush adapted for cleaning the interior of apparatus illustrated in preceding figures.

The example of apparatus shown in Figs. 1 and 2, which has been found to give good results in practice as a steam generator, comprises a single compound tube composed of narrow rings 1 and conducting plates 2 of larger diameter that separate the rings and are arranged alternately therewith in such a manner as to form a continuous tube. The rings 1 and plates 2 are held together by means of bolts 3 that pass through bolt-holes 4 in the plates 2 inside the rings 1, and are furnished with heads 5 and box-nuts 6 that are faced true; and that when screwed home cause the components 1 and 2 of the tube to be compressed between the end plates 2^a. The rings 1 are cut from tubes of suitable diameter, and one face of each ring—viz., that shown to the left of each ring in Fig. 1—is of reduced breadth, so that each of the plates 2 is clamped between a broad surface on one side and a narrow one on the other. The section of a ring 1 may be tee shaped, or it may be trapezoidal, or polygonal, so long as a broad and a narrow face are presented.

In addition to the bolt holes 4 there are formed in the plates 2 slots 7 that radiate from a central hole 8, and terminate at the inner periphery of the rings 1. The slots 7 in each plate do not lie in the same direction as, but are arranged at right angles to, those in the adjacent plates, as shown in Fig. 2, where the aperture in the plate to the rear of that fully shown is indicated in dotted lines. From the bolt holes 4 there extend radially to the inside of the rings 1 slots 9 into which, to insure that the rings 1 are in alinement with one another, there are driven between these rings and the bolts 3 small rods 10 whose cross section is such as not to inter-

fere with circulation along the bolts 3. These rods 10 may conveniently be all of tee cross-section, as shown in Fig. 2.

Composite tubes of the type shown in Figs. 5 1 and 2 can be cleaned by means of a tee-headed rod such as that shown in Figs. 3 and 4; the cleaning of the apparatus being effected by inserting the head 11 of the rod through the slots 7 in the outer plate, resting the rod 12 in the hole 8, and by an alternately reciprocatory and longitudinal movement passing the rod 12 up the entire length of the tube, and its head 11 successively through the slots 7 and the spaces which are between the plates 2 and which are fitted by the head 11.

It will be seen from Fig. 2 that each central hole 8 and its extensions 7 divide that portion of the corresponding conducting plate 1 which is located within the tube into segments the edge of each of which does not extend inwards beyond a straight line connecting together the peripheral ends of the edge in question; consequently the edges will not, as they would if they were to project inwards in the manner stated, be liable to be warped by changes in temperature and so to prevent the proper insertion of the cleaning tool through the perforations 8 and extensions 7 and into the spaces between the plates.

The horizontal steam generating section shown in Figs. 5 to 7 is constructed as described with reference to Figs. 1 and 2, but is provided with a dummy end 13 to facilitate cleaning. This dummy end is made with slots 14 that resemble the slots 7 and is fastened down by nuts 16 screwed on to two of the bolts 3; it is, moreover, provided with a tubular extension 15 which forms a steam chest, is furnished at its side with a screwed steam outlet 17, and is closed by the true end 18 which is held down by the box nuts 6 on the bolts 3. For cleaning purposes the end 18 is removed, the bolts not provided with nuts 16 are withdrawn, and the section is cleaned in the manner already described by means of a rod such as is shown in Figs. 3 and 4.

Water is supplied to the section by means of a tee connection 19 at the end opposite to 50 the steam chest 15. Through this extension there passes the lowest removable bolt 3, and there are formed in the end plate suitable openings 21 around the bolt to allow the water to pass from the tee piece to the interior of the section. It is especially important that the cross-section of the rods 10 should in this instance be such as to permit free circulation to take place; they may suitably be of tee section as shown in Fig. 6. The location of the hole for the lowest of the removable bolts 3 and its bottom extension enables the scale that has been detached by the tool 12 to be scraped out of the tube.

Apparatus constructed as above described 65 is particularly suitable for employment in

the manufacture of flash-boilers. Many modifications in detail may of course be made; the broad surface of each ring may, for instance, as shown in Fig. 8, be lined with circular grooves 22, or there may be provided in each ring, as shown in Fig. 9, a large groove 23 into which a plate 2 can be compressed by the corresponding annular projection 24 upon an adjacent ring; or a plate may in its manufacture be formed with a 75 circular indentation 25 that fits into the groove 23 and is adapted to receive the projection 24. Again, where there is to be no great heat, as in the case of radiators, both faces of a ring may, as shown in Fig. 10, be 80 broad and furnished with grooves 26; suitable packing may in this case be inserted, or the ring may be stamped out of suitable packing material. Again, the ring 1 and the indentations 25 upon the plates 2 may, as 85 shown in Fig. 11, be so formed that but one ring is required between a pair of plates, and the next pair of plates (one plate being common to both of the pairs referred to) will abut against one another at 27 and yet will 90 be correctly spaced apart. Again, the indentations 25 may, as shown in Fig. 12, be such that no separate rings are required. Again, the rings 1 may be cast upon the plates 2 and form part of them as shown in 95 Fig. 13. Moreover, the rings 1 and the plates 2, instead of being circular, may be of oval or approximately oval form, as shown in Fig. 14, or of rectangular form, as shown in Fig. 15, the slots 7 and the bolt-holes 8 100 being then disposed in the manner indicated in these figures.

Where, as in the modified construction shown in Figs. 16 and 17, but one row of tubes is employed, a good form of plate is a 105 heart shaped one, the apex of the heart being removed, and a continuous reduction in the width of the plate extending outside the ring taking place from its upper portion to its lower point 30 which is exposed to the flame 110 of the burners 31. At the top of the heart there is provided a baffle 32 to return the gases downwards towards the center 33 of the heart before they are allowed to escape. In arrangements comprising more than one 115 row of tubes a construction similar to that last described may also advantageously be adopted in the case of the row last exposed to the action of the hot gases.

An effect similar to that of the apparatus 120 last described, but more marked, is produced by means of the arrangement shown in transverse section in Fig. 18, wherein each plate 2 is of spiral form, and attains its maximum breadth at a point 34 near a horizontal 125 line through the center of the ring 1. The flame enters at 35 and the products of combustion pass between the plates 2 below the rings 1, circularly along the bottom, up the side 36, and after passing over the top, are 130

directed by means of the baffle 37 towards the point 34 at which they escape in a cooled condition. Tubes provided with spiral plates of the kind in question are best arranged in pairs and may conveniently have their points of egress away from each other, as shown in Fig. 18.

Figs. 5, 6 and 7, Fig. 16 and Fig. 18 illustrate arrangements in which heat is transmitted from one fluid to another by means of conducting plates that are immersed in both fluids and each of which has portions projecting into different parts of a fluid to different extents according as the said parts are respectively lower or higher in temperature, the extent to which the plates project into the different parts of the fluid being inversely proportional to the corresponding differences of temperature between the plates and the fluid.

For heating air by means of steam or hot water the arrangement shown in Fig. 16 may be employed, the air flowing upwardly between the plates, while the steam or water passes through the tubular space within the rings. The plates may moreover in apparatus of this type in some instances be of the form shown in Fig. 2, or of that shown in Fig. 15. For some boilers it is advisable to pass the hot gases through the tubes inside the rings. When this is done, soot is liable to accumulate in the tubes; and for its removal there is provided a wire brush, of the kind shown in Figs. 19 and 20, that can be used in the manner already described with reference to and shown in Figs. 3 and 4. In some cases bolts 3 may be dispensed with, the rings 1 and plates 2 constituting each section being tinned, erected, and clamped, then heated until they unite, when the clamps can be removed; this mode of manufacture is particularly suited to indented plates and for apparatus intended for low temperatures and small pressures. In boilers having inclined tubes the tubes may be cleaned from the lower or water feed end, the dummy end being fitted there with suitable water connections. Where desirable, non-corrosive substances such as glass, earthenware, or vulcanite may be used, their surfaces and sections being proportioned to their conductivity.

What I claim is:—

1. Apparatus for transmitting heat from one fluid to another, comprising a wall arranged between the two fluids and having heat conductors in connection therewith, each of said conductors having portions projecting from said wall into one of said fluids at different parts thereof to different extents and more or less according as said parts differ respectively less or more in temperature from the conducting portions in contact therewith.

2. Apparatus for transmitting heat from one fluid to another, comprising a wall ar-

ranged between the two fluids and having heat conducting plates in connection therewith, each of said plates having portions projecting from said wall into one of said fluids at different parts thereof to different extents and more or less according as said parts differ respectively less or more in temperature from the plate portions in contact therewith. 70

3. Apparatus for transmitting heat from one fluid to another including a wall located between said fluids and comprising heat conductors each projecting from said wall into both fluids and each having portions extending into one of said fluids at different parts thereof to different extents and more or less according as said parts differ respectively less or more in temperature from the conductor portions in contact therewith. 75

4. Apparatus for transmitting heat from one fluid to another including a wall located between said fluids and comprising heat conducting plates each projecting from said wall into both fluids and each having portions extending into one of said fluids at different parts thereof to different extents and more or less according as said parts differ respectively less or more in temperature from the plate portions in contact therewith. 80

5. For transmitting heat from one fluid to another, a tube the wall of which comprises transverse heat-conducting plates each of which projects inwards and outwards of the tube and has portions projecting into different parts of one of said fluids to different extents and more or less according as said parts differ respectively less or more in temperature from the plate portions in contact therewith. 95

6. For transmitting heat from one fluid to another, a tube the wall of which comprises transverse heat-conducting plates each of which projects inwards and outwards of the tube and has portions projecting outwards of the tube into different parts of one of said fluids to different extents and more or less according as said parts differ respectively less or more in temperature from the plate portions in contact therewith. 105

7. For transmitting heat from one fluid to another, a tube the wall of which comprises transverse heat-conducting plates each of which projects inwards and outwards of the tube and has portions projecting outwards of the tube into different parts of one of said fluids to different extents and more or less according as said parts differ respectively less or more in temperature from the plate portions in contact therewith, the portion of each of said plates within the tube having a central hole extending radially at one or more parts to the internal periphery of the tube. 110

8. For transmitting heat from one fluid to another, a tube the wall of which comprises transverse heat-conducting plates each of which projects inwards and outwards of the 130

tube, the portion of each of said plates within the tube having a central hole extending radially to the internal periphery of the tube and dividing such portion of the plate into segments the edge of each of which does not extend beyond a straight line connecting together the peripheral ends of the edge in question.

9. For transmitting heat from one fluid to another, a tube the wall of which comprises transverse heat-conducting plates each of which projects inwards of the tube, the portion of each of said plates within the tube having a central hole extending radially at one or more parts to the internal periphery of the tube and dividing such portion of the plate into segments the edge of each of which does not extend beyond a straight line connecting together the peripheral ends of the edge in question, the radial extensions in adjacent plates being out of alinement with each other.

10. For transmitting heat from one fluid to another, a tube the wall of which comprises transverse heat-conducting plates each of which projects inwards of the tube, the portion of each of said plates within the tube having a central hole extending radially at one or more parts to the internal periphery of the tube, such radial extensions in adjacent plates being out of alinement with each other and said plates being also provided, at the internal periphery of the tube, with holes in alinement with one another and adapted to enable scale that has been detached within the tube to be removed therefrom.

11. For transmitting heat from one fluid to another, a tube the wall of which comprises transverse heat-conducting plates each of which projects inwards and outwards of the tube, the outwardly projecting portion having its periphery gradually receding from

said tube up to a point and then approaching said tube.

12. For transmitting heat from one fluid to another, a tube the wall of which comprises transverse heat-conducting plates each of which projects inwards and outwards of the tube, the outwardly extending portion gradually extending from the tube to different extents in opposite directions from the point nearest the tube.

13. For transmitting heat from one fluid to another, a tube the wall of which comprises transverse heat-conducting plates each of which projects inwards and outwards of the tube, the outwardly projecting portion of each plate having a circular periphery eccentric to said tube.

14. For transmitting heat from one fluid to another, a tube the wall of which comprises transverse heat-conducting plates each of which projects inwards and outwards of the tube and has portions projecting outwards of the tube into different parts of the hotter of said fluids to different extents and more or less according as said parts are respectively lower or higher in temperature, the portion of each of said plates within the tube having a central hole extending radially to the internal periphery of the tube and dividing that portion of the corresponding plate which is located within the tube into segments the edge of each of which does not extend beyond a straight line connecting together the peripheral ends of the edge in question.

Signed at London, England, this 25th day of February, 1905.

WILLIAM JOSEPH STILL.
